SAFETY RAZOR

William James Davies, Glasgow, Scotland, assignor to Arthur Watson Legat, Paisley, Renfrewshire, Scotland

Application May 28, 1940, Serial No. 337,575
In Great Britain June 8, 1939

2 Claims. (Cl. 30—68)

The invention relates to safety razors of the type in which a thin flexible razor blade is transversely flexed by pressure against an outer concave cover member.

An object of the invention is to provide a simplified construction of safety razor of the above noted type.

A safety razor, according to the invention, incorporates a cover plate presenting an inner concave face, a slot formed in said cover plate and extending parallel to an edge thereof, means for securing the blade against the concave face of the cover plate with the cutting edge of the blade projecting into the slot and the marginal part of the blade adjacent to said edge bearing against the inner longitudinal boundary of the slot, a guard bar presented by the marginal portion of the cover plate on the outer side of the slot and a handle member for the holder.

Desirably, the cover plate is formed with two spaced parallel slots which are spaced apart at equal distances from the longitudinal median plane of the cover plate, the blade being held against the concave face of the cover plate with each cutting edge projecting into a slot and the marginal parts of the blade adjacent to said edges bearing against the inner longitudinal boundaries of the slots.

The blade is held in position by means including studs, pins or the like which project from the concave face of the cover member and are preferably located on the longitudinal median plane of the cover member.

The studs or the like penetrate holes formed in the blade which is held in a flexed condition by means of a longitudinal cotter passed through aligned transverse holes in the studs or the like.

The cutting edge or edges of the blade may be arranged flush with or slightly within or slightly projecting beyond the outer surface of the cover member.

As both sides of the cutting edge or edges are exposed, the blade may be easily cleaned without removal from the holder.

The invention will now be described with the aid of the accompanying drawing in which Fig. 1 is an end view; Fig. 2 a front view and Fig. 3 a plan of a safety razor constructed according to one embodiment of the invention.

Referring to the drawing, 1^a is the cover plate and 10' the handle. Projecting from the concave face of the cover member 1^a are two studs 4^a having aligned transverse holes. The cover member 1^a is formed with two spaced parallel slots 6^a so located that when the blade 7^a is 55

placed over the studs 4^a and flexed by the insertion of a cotter pin 11 through the holes each cutting edge of the blade 7^a projects into its respective slot with the part of the blade adjacent to such cutting edge bearing against the inner longitudinal boundary of the slot while a marginal portion of the cover member on the outer side of the slot presents a guard bar for the cutting edge. The cotter 11, see Fig. 2, is tapered or pointed to facilitate the insertion of the cotter through the aligned holes in the studs 4^a.

The cotter 11 may be integral with the handle, the cotter and handle being made of wire or the like. As shown in Figs. 1, 2 and 3 the handle 15 is conveniently formed of a wire 10 bent at a point a spaced from one end thereof at approximately a right angle, the portion of the wire from said bend to the said end of the wire constituting the cotter 11. At a point b spaced from said first bend the wire is bent inwardly substantially at a right angle so as to lie parallel with the cotter 11, then again at a point c spaced from the second bend and substantially coinciding with the crossing line of the median longitudinal and transverse planes of the cover member 1^a to form a third bend, the wire between the third and first bends forming a bracket 3^a. At a suitable distance from the third bend the wire may be bent into a loop to form the handle 20 proper 10'. The portions of the wire on each side of and adjacent to the return bend of the loop are spaced or spread apart so that the outer end of the handle is wider than the inner end which is adjacent to the third bend c, whereby 25 to afford a convenient grip. From the inner end of the handle part the wire is bent to lie contiguous with the portion of the wire between the third and first bends and terminates in the form of a projection 10'', a short distance beyond the cotter portion 13. The adjacent parts d of the wire at the first bend may be soldered, welded or otherwise secured together as indicated at d.

The end of the cover member 1^a adjacent to the first bend a of the wire 10 is provided with a notch 12, so that when the studs 4^a are slid on to the cotter 11, the notch 12 engages the projections 10'' and the cover member 1^a is locked in shaving position. When unlocked the cover member 1^a may be shifted angularly about the cotter 11 as an axis, so as to expose the blade 7^a for convenient cleaning or for packing the razor in compact form. If desired the cover member 1^a may be notched at each end so as to be reversible.

The razor of the invention is non-clogging, for example, in the case of surgical shaving, long hairs may be shaved off without clogging the blade.

I claim:

1. A safety razor comprising a wire having a part thereof bent into the form of a loop, with the parts forming the loop being spaced to afford a handle, the portions of the wire beyond one end of the loop being brought together and bent in parallel in the plane of said handle and at substantially right angles to the direction of said handle, and again bent at substantially right angles to the first bend so as in conjunction with the handle to form substantially a Z-shaped figure, one of the portions of the wire being bent at the end of the last bent section in a direction reverse to the first bent portion beyond the handle and forming a cotter pin free at its distal end and supported at its proximal end, the other portion of the wire terminating in a stop adjacent to said proximal end of the cotter pin, a cover member having slots parallel to said cotter pin, spaced studs extending from said cover member and having aligned apertures through which said cotter pin extends, said cover member also having a notch in which the portion of the wire forming said stop is received, said cover member having a curved under face, and a thin flexible blade interposed between said cotter pin and said 30

cover member and having cutting edges exposed by the slots in the cover member, said blade being held by said cotter pin in flexed condition against said under face.

5 2. A safety razor comprising a wire bent to form a handle, the portions of the wire beyond one end of the handle being brought together to form a twin wire, said twin wire being bent in the plane of the handle, one portion of the wire beyond the handle being bent to form a cotter pin free at its distal end and supported at its proximal end, the other portion of the wire beyond the handle terminating in a stop located adjacent to said proximal end of the cotter pin, a cover plate member extending lengthwise of said cotter pin and having slots extending parallel to said cotter pin, said cover member also having a notch in which the portion of the wire forming said stop is received, said cover plate having a concave under surface, spaced studs projecting from said cover member and having aligned apertures through which said cotter pin extends, and a thin flexible blade having cutting edge portions, said blade being interposed between said cotter pin and said under surface and held by said cotter pin in flexed condition against the under surface of the cover member with said cutting edge portions exposed by the slots in the cover member.

WILLIAM JAMES DAVIES.
